UNITED STATES PATENT OFFICE.

STEPHEN I. FEKETE AND STUART G. BAITS, OF DETROIT, MICHIGAN, ASSIGNEES TO
ESSEX MOTORS, OF DETROIT, MICHIGAN, A CORPORATION OF MICHIGAN.

INTERNAL-COMBUSTION ENGINE.

Application filed August 20, 1919. Serial No. 318,832.

To all whom it may concern:

Be it known that I, STEPHEN I. FEKETE, a subject of the King of Hungary, residing at Detroit, county of Wayne, State of Michigan, and STUART G. BAITS, a citizen of the United States, residing at Detroit, county of Wayne, State of Michigan, have invented a certain new and useful Improvement in Internal-Combustion Engines, of which the following is a specification, reference being had therein to the accompanying drawings.

Our invention has for its object a new and improved high speed internal combustion engine of the four-cycle type. The engine embodying our invention is particularly intended for racing purposes and for aviation work, the particular object being to produce an engine which will develop the largest possible horse-power for a given cylinder capacity. The engine embodying our invention is especially well adapted to small cylinder sizes, such for instance as are now commonly employed in racing engines.

As is well understood by those skilled in the art, one of the limiting features of internal combustion engines of the four-cycle type is the failure of the engine to draw in through the intake valves a sufficient quantity of the carbureted mixture to completely fill the combustion space, particularly when the engine is running at extremely high speed. Accordingly, it is well recognized that there must be employed large inlet and exhaust passages, and these passages must be as straight as possible to lessen the attenuation of the stream of gas due to its inertia.

These results may be best accomplished by the use of overhead inlet valves which allow the gas to flow downward directly into the top of the cylinder, but great difficulty has been experienced in connection with such engines, owing to the fact that when driven at high rates of speed, the strain placed upon the valve-operating mechanisms is too great and they rapidly become worn and inaccurate in their operation.

To overcome these various difficulties, we place the exhaust valve in a pocket on the side of the cylinder so that the gas may enter through the top of the cylinder and pass out at a lower point through the side. In this way, the exhaust valves may be operated by a cam shaft placed below the

cylinders and adjacent the crank shaft of the engine. Since the exhaust valves must open against pressure in the cylinders, this is the most satisfactory construction, as there are no rocker arms or long rods or pivots to wear, spring or expand. The inlet valves are inverted in the head and are operated by direct action of an overhead cam shaft through a valve tappet acting directly on the end of the valve stem. In this way the use of rocker arms, pivots and bearings in the valve-operating mechanism is altogether done away with. Therefore, while retaining all the advantages of the overhead valve type of engine, all the difficulties resulting from the use of rocker arms and the like are obviated.

Another important feature of our invention consists in the fact that the spark plug may be located in the head of the engine midway between the inlet valve and the exhaust valve and centrally of the combustion chamber which is the best possible position for the spark plug. Furthermore, the engine in its preferred form is provided with two inlet valves and two exhaust valves for each cylinder, and in this case, the spark plug is located at about the centre of the space between the four valves.

The construction of the engine and the relation of the inlet valve and the exhaust valve and the spark plug also make possible the more effective cooling of all parts of the cylinder block, particularly the valve seats and metal surrounding the spark plugs.

The invention will be fully understood from the following description when taken in connection with the accompanying drawings, and the novel features thereof will be pointed out and clearly defined in the claim at the close of this specification.

In the drawings, Fig. 1 is a vertical section of an engine embodying our invention.

Fig. 2 is a top plan view of one end of a cylinder block showing the relation of the various parts.

Referring now to the drawings, at 11 and 12 are shown two cylinders of a four-cylinder internal combustion engine. The block or cylinder casting is designated 13. This is provided with a removable head 14. The removable head 14 forms a combustion chamber 15 over the cylinder and extends laterally (see Fig. 2) to form a pocket for 110

2
two exhaust valves 16 and 17. The exhaust valves are provided with the ordinary stem 18 sliding in a proper guide 19 and operated by a valve tappet 20, a cam 21 and 5 a cam shaft 22. The cam shaft is driven from the crank shaft of the engine (not shown) by suitable gears.

Each cylinder is provided with a pair of inlet valves 23 and 24, each carried in a 10 suitable guide 25 and having a valve stem 26 actuated by a tappet 27. Lengthwise of the top of the motor, is located a cam shaft 28 provided with cams 29 which act on the 15 respective valve tappets 27. The cam shaft 28 is carried in a housing 30 forming part of the removable head 14 of the engine. The cam shaft is driven by a train of gears 31, 32, 33 and 34, the last being located on the 20 exhaust cam shaft 22. It will be understood that any suitable means for driving the two cam shafts in time with each other and with the crank shaft may be employed.

At 35 is shown a spark plug which, as will be seen, is located at about the center 25 of the combustion space, being between the

pairs of valves and substantially equidistant from the valves of each pair, said spark plug being also quite close to the inlet valve so that the progress of combustion will be substantially uniform in all directions. It 30 will also be seen that the spark plug is well cooled by the water spaces 37 and 38.

What we claim is:—

An internal combustion engine the cylinders of which have a removable head and 35 having exhaust valves in pockets at the sides of the cylinders and operated by a camshaft below the cylinders, and inverted inlet valves over the cylinders, operated by mushroom valve tappets and a camshaft 40 above the cylinders, the said inverted valves and valve tappets being guided in a housing integral with and mounted on said removable head and containing the camshaft and the inlet passages. 45

In testimony whereof we affix our signatures.

STEPHEN I. FEKETE.
STUART G. BAITS.
